UNITED STATES PATENT OFFICE.

WILLIAM E. PRINDLE, OF MANITOWOC, WISCONSIN.

DRYING APPARATUS.

1,085,939.

Specification of Letters Patent.

Patented Feb. 3, 1914.

Original application filed February 28, 1912, Serial No. 680,464. Divided and this application filed November 11, 1912. Serial No. 720,569.

To all whom it may concern:

Be it known that I, WILLIAM E. PRINDLE, a citizen of the United States, and a resident of Manitowoc, in the county of Manitowoc 5 and State of Wisconsin, have invented certain new and useful Improvements in Drying Apparatus, of which the following is a specification, reference being made to the accompanying drawings.

10 My present invention relates to drying machines in general, and more particularly to an improved type of mechanical drier adapted for use in drying wet material; and is a divisional application of my co-pending 15 application for a drier, Serial No. 680,464, filed February twenty-eighth, 1912.

One of the principal objects of my invention is the provision of an improved drying apparatus wherein high temperatures 20 are effectively employed and applied where the material is wet and cold, correspondingly reduced temperatures where the material is partly dried, and low temperatures where the drying is completed; and another 25 object of my invention is the provision of novel means in a drier adapted to control the admission of cold air therein for the purpose of quickly cooling down the drier when desired.

30 These together with such other objects as may hereinafter appear or are incident to my invention I attain by means of a construction illustrated wherein,

Figure 1 is a longitudinal sectional view 35 of my improved apparatus, the cylinders therein being shown broken away in order to accommodate the figure in the drawing.

Figure 2 is a modification of the structure in Figure 1.

40 Figure 3 is an enlarged sectional view of the rear end of the drier as shown in Figure 1.

Figure 4 is a rear elevation of Figure 1.

45 Figure 5 is a section through the apparatus on the line II of Figure 1.

Broadly speaking, the invention comprises the application of graduated temperatures to the material in the drier, ranging 50 from the desired high temperature at a point where the wet and cold material enters, to a correspondingly low temperature toward the rear end of the drier, where the material is in a dry state, such application resulting in the material being discharged 55 as a uniformly dried product and without

incurring any risk of scorching the material at any stage of the drying operation, which is an improvement on the method adopted in the type of drier commonly in use. In a more exclusive sense the present invention 60 purposes to provide novel means in an apparatus of the character described whereby the interior of the drier can be quickly and positively cooled down to any desired extent as the occasion requires.

65 In carrying out my invention, as illustrated in the preferred form in the accompanying drawings, I provide a drier shell or outer cylinder 6 preferably lying at an angle to the horizontal, and adapted to have rotation through a gear 7 thereon having driving engagement with a pinion 8 mounted for movement on the base 9 and driven from any suitable source of power at hand. The rear or discharge end of the cylinder 70 has free rotative movement within a flanged hood 10 securely mounted on a base 11 and further held in position by the braces 12, the said hood being conformed to entirely 75 inclose the rear end of the cylinder any longitudinal creeping thereof being provided against through thrust rollers 13, which bear against vertical shoulders of tires 7a 80 peripherally formed on the drier.

85 The hood 10 at the rear end of the drier is further provided with a discharge hopper 14 leading from the discharge end of the cylinder to a receptacle 15 within which I provide a conveyer 16 for conveying the dried material to any suitable depository.

90 Centrally suspended within the drier 6 is an inner hot air conveyer 17 extending longitudinally therethrough, and having its rear end 17a projecting through the hood 10 and its forward end 17b in communication 95 with a tempering or furnace chamber 18, or other source of heat, preferably through a fixed extension 19 about which it is adapted to rotate.

100 Surrounding the forward end 17b of the inner cylinder and providing a bearing therefor, is a stationary bonnet 20 mounted on a base 21 and having connection with an exhaust fan 22 by means of a funnel 23. The bonnet, which carries a feeding member 24, opens into the feed end of the drier, and an annular shoulder interiorly formed on the drier frustum connection 25 rotates about a bearing surface on the bonnet.

105 The hot air conveyer is suspended within 110

the drier by means of spiders 26 and 27 which have their outer extremities bolted to the inner walls of the outer chamber. The inner portion of the spider 26 is fastened 5 to the outer walls of the inner cylinder so that both cylinders have similar rotative movement, and the inner portion of the spider 27 carries a ring 27^a having peripheral contact only with the inner cylinder in 10 order to allow for any expansion or contraction of the cylinders.

Arranged at intervals along the length of the inner chamber are a series of outlet openings 28 which are preferably protected 15 from the material in the drier by elongated hoods 29 which have their openings directed toward the rear end of the drier. This arrangement permits the heated air which enters the conveyer from the tempering chamber to pass through the hooded openings, and also affords opportunity for the highest 20 temperatures passing through the outlets adjacent the feed end to come directly in contact with the material which at this point is 25 wet and cold. The heated gases circulating in the drier and also passing through the conveyer gradually part with their heat through absorption and radiation, so that moderating temperatures are applied to the 30 partly dried material on its progression rearwardly, graduating to comparatively low temperatures at the rear end where the 35 drying operation is completed. The suction fan creates and maintains a constant circulation of heated air passing through the entire series of outlets to the material as it is cascaded, the heated air moving at constantly decreasing velocity and at diminishing 40 temperatures as the material in its progression toward the hopper becomes drier and lighter until the material is finally discharged amid gases of a very low temperature moving at a very low velocity.

The wet material is first fed into the front 45 end of the drying chamber through the spout 24 and during the revolving of the apparatus is cascaded by the longitudinal lifting blades 30 bolted on the inside of the drying chamber and the lifting blades 31 50 similarly secured to the outer walls of the inner cylinder.

Referring now more particularly to Figure 3 it will be seen that the inner cylinder has its walls perforated for a slight portion 55 of its length to provide a series of annular ports 32, the ports being located within the drier and in close proximity to the hood, and surrounded and protected against the entrance of foreign matter by a shield 33 having its opening 34 facing rearwardly. These 60 ports normally serve the same purpose as the outlets 28, but they also have an additional function as will be explained.

In this connection I provide a reciprocating

piston 35, within the conveyer and adjacent the rear end thereof, to normally close the opening in the projecting end which opens to the atmosphere. This piston carries a rod 36 operating in guide members 37, 37, which rod is adapted to impart longitudinal movement to the piston inwardly to a position either in part or wholly past the ports 32, permitting the induction of cold air into the drier by the suction fan to any desired extent through the said opening 17^a and the ports 32. It is apparent then that the piston has movement to and from operative position to open and close the ports, and is provided to regulate temperatures and control the admission of cool air in the drier.

The modified construction as disclosed in Figure 2 shows the tires 7^a peripherally mounted on the projecting ends 17^a and 17^b of the conveyer 17 instead of on the outer shell as 85 in Figure 1. It is obvious that this improved arrangement is simple and economical, and is particularly advantageous when applied to the smaller makes of drying machines.

Having thus described my invention and 90 illustrated its use, what I claim to be new and desire to secure by Letters Patent is the following:—

1. In a drier, the combination with an inclosed drying chamber provided with a feed member and a discharge outlet, of an inner cylinder having one end thereof leading to a source of heat and its other end extending through the drying chamber, and means to provide communication between the inclosed 95 drying chamber and the atmosphere through the inner cylinder.

2. In a mechanical drier, the combination of a closed outer shell, an inner conveyer having communication at one end with a source of heat and having its other end opening outwardly through the shell to the atmosphere, said inner conveyer being provided with outlet openings in its walls, and means to control the admission of cool air 105 into the drier through the said conveyer.

3. In a drying apparatus, the combination of an outer shell, an inner cylinder having its rear end opening to the atmosphere and its front end communicating with a source 115 of heat, said inner cylinder having outlet openings in its walls providing communicating passages for the heated air to the outer shell, and reciprocating means mounted within the inner cylinder to govern the 120 said openings in the rear end thereof for the admission of cool air into the drier.

4. In a drier, a drying shell, an inner hot air cylinder having one end thereof opening to the atmosphere and provided with a port 125 in its walls affording a passage for the hot air therefrom to the drying shell, and a piston in the cylinder normally closing the

opening in the rear end thereof and mounted for operative movement substantially to a position past the said port.

5. In a drying apparatus, an inclosing outer shell, a cylindrical hot air conveyer having its rear end opening through the outer shell to the atmosphere, said conveyer having its walls perforated to provide a series of ports normally affording a passage 10 for the hot air to the outer shell, a reciprocating piston mounted for movement in the conveyer which when in normal position closes the rear end thereof and when moved to operative position admits cool air into 15 the drier through said ports.

6. In a drier, an outer shell, an inner hot air cylinder projecting through the outer shell and having that portion of its length within the shell perforated for the passage 20 of hot air to the outer shell, a piston in the cylinder, and means to actuate the piston.

7. In an apparatus of the character described, an outer cylinder having a feed member and discharge means, an inner cylinder suspended therein having communication with a source of heat and having one end thereof opening to the atmosphere, the walls of the said inner cylinder being perforated to provide a communicating passage 25 for the heated air to the outer cylinder, an annular shield surrounding the said passage having its opening facing in a direction toward the discharge end of the drier, and reciprocating means in the inner cylinder which on actuation opens and closes the said passage to the atmosphere.

8. In a drier, the combination of an inclosed drying chamber provided with a feed member and a discharge outlet, an inner cylinder communicating with a source of heat and lying in the drying chamber, and means to provide communication between the drying chamber and the atmosphere through the inner cylinder.

45 9. In an apparatus of the character described, an outer shell, an inner cylindrical

conveyer extending through the walls of the shell, one end thereof communicating with a source of heat and the other end opening to the atmosphere, said conveyer being provided with a series of guarded air passages in its walls leading to the outer shell, and reciprocating means to open and close the open end of the conveyer, whereby cool air is admitted into the outer shell through the 55 said air passages, substantially as described.

10. In a rotary drier, the combination of an outer inclosed shell having a feed opening at its forward end and a discharge outlet at its rear end, an inner hot air conveyer extending through the shell and provided with an opening at its forward end leading to a source of heat, said conveyer having its walls perforated at intervals along its inclosed length and so arranged 60 that highest temperatures are directed to material when first fed into the interior of the drier with the application of correspondingly diminishing temperatures to the material as it parts with its moisture, and a 65 controlling member normally closing the rear end of the conveyer and adapted to have movement therein to permit the entrance of cool air into the drier, in the manner set forth.

11. In a drier, the combination of an inclosed drying chamber provided with a feed member and a discharge outlet, an inner cylinder communicating with a source of heat and lying in the drying chamber, and 80 means to provide communication between the drying chamber and the atmosphere through the inner cylinder, including a valvular device for controlling the admission of air.

In testimony whereof I have hereunto signed my name in the presence of the two subscribed witnesses.

WILLIAM E. PRINDLE.
